UNITED STATES PATENT OFFICE.

WILLIAM F. FANNING, OF CHICAGO, ILLINOIS.

BOTTLE-FILLING MACHINE.

SPECIFICATION forming part of Letters Patent No. 763,601, dated June 28, 1904.

Application filed October 23, 1903. Serial No. 178,194. (No model.)

To all whom it may concern:

Be it known that I, WILLIAM F. FANNING, a citizen of the United States of America, and a resident of Chicago, Cook county, Illinois, 5 have invented a certain new and useful Improvement in Bottle-Filling Machines, of which the following is a specification.

My invention relates to machines for filling bottles—preferably quite a number of bottles 10 at one time; and it contemplates a machine of this character which is capable of measuring off certain quantities of liquid from a main reservoir to subreservoirs and of then, through the medium of the same pipes and passages, 15 the pipes being endwise adjustable, discharging said certain or predetermined quantities of liquid into the bottles; and it also contemplates the provision of certain details and features of improvement tending to increase the 20 general efficiency of a bottle-filling machine of this particular character; but the nature and advantages of my invention will, however, hereinafter more fully appear.

In the accompanying drawings, Figure 1 is 25 a front elevation of a bottle-filling machine embodying the principles of my invention. Fig. 2 is a horizontal section on line 2 2 in Fig. 1. Fig. 3 is a vertical section through the upper portion of the machine on line 3 3 30 in Fig. 1. Fig. 4 is a detail view similar to Fig. 3, showing one of the filling and discharge pipes with which each reservoir is provided in a depressed position—that is to say, in position to discharge the contents of the subreservoir into a bottle.

As thus illustrated, my improved bottle-filling machine may comprise an upright frame or body A of any suitable form or construction. A main reservoir B is mounted upon 40 the upper portion of this frame or body, and in order that the correct or desired quantities of liquid may be accurately measured off before the same is discharged into the bottles the said reservoir is provided with a plurality 45 of depending subreservoirs C, which are preferably of glass. These subreservoirs may consist of glass cylinders held in place against the bottom of the main reservoir by clamp-

ing-bolts and plates e and c'. As shown in the drawings, each subreservoir is provided 50 with an air-vent in the form of a pipe c², which extends from a desired point in the reservoir to some distance above the main reservoir. The bottom of each subreservoir is also preferably provided with a stuffing-box c³, 55 and the top wall of each subreservoir is provided with stuffing-boxes c⁴ and c⁵, one for the pipe c² and the other for the pipe c⁶. As will be observed, these pipes are all arranged vertically, the pipes c⁶ being connected for simultaneous vertical reciprocation by means of a frame or member x. The pipes c⁶ work in the stuffing-boxes c³ and c⁵ and are each provided with an upper inlet c⁷ and a lower outlet c⁸. Cone-shaped portions c⁹ are preferably secured in the lower ends of the pipes c⁶, and the flaring or funnel-shaped guards c¹⁰ are mounted to slide upon the lower ends of these pipes. The pipes c² can be adjusted up and down, so as to measure off different quantities 60 of liquid from the main reservoir to the subreservoirs. Normally the liquid flows from the main reservoir through the inlet-openings c⁷, thence through the pipes c⁶, and out into the subreservoirs through the discharge-openings c⁸. With this arrangement the liquid can only rise in the subreservoirs until it reaches the lower ends of the pipes c². The escape of the air from the subreservoirs being thus cut off, the liquid can rise no farther, and in this 70 way the desired or predetermined quantities of liquid are measured off into the subreservoirs.

The pipes c⁶ are adapted to be manually reciprocated through the medium of a treadle 85 D, a cross-bar d, and the vertically-arranged connecting-rods d', which latter are connected at their upper ends with the frame or member x. Springs d², extending between the cross-bar d and the bottle-support E, serve as the 90 means for keeping the pipes c⁶ in their normal or elevated positions.

The bottle-support E can be mounted on the main frame or body. As shown, it is preferably provided with a vertically-adjustable platform e, adapted to be raised and low-

ered by means of the adjustable screw e' , so as to adapt the machine for use in connection with bottles or other receptacles of different heights and sizes. This adjustable platform 5 is preferably mounted on rods e^2 , adapted to reciprocate vertically in the casing or guides e^3 , which latter are secured to the bottom of the horizontally-disposed support E. The bottles can be arranged in place on the plat- 10 form e , and by then depressing the lever D the pipes c^6 can be depressed until their lower ends c^9 enter the bottles to the desired or nec- 15 essary extent—that is to say, until the openings c^8 are within the bottles. In descending 15 the funnel-shaped guards c^{10} tend to center or bring the bottles into position to receive the lower ends of the pipes if the bottles have not been accurately arranged on the platform, and, furthermore, these guards then rest upon 20 the tops of the bottles, and thus prevent the liquid from escaping upwardly. When the pipes c^6 have been adjusted downwardly to an extent to bring the inlet-opening c^7 to a point 25 near the bottom of the subreservoirs, the liquid in these subreservoirs then flows out 30 through the pipes and into the bottles. As soon as the subreservoirs have been emptied of their contents the pipes c^6 are then allowed to rise and in so doing reestablish commun- 35 cation between the main reservoir and the subreservoirs, thus effecting a refilling of the latter.

Thus it will be seen that I not only provide a bottle-filling machine wherein either small 35 or large quantities of liquid may be accurately measured off from a main reservoir to sub- reservoirs, so that only the desired quantities will be discharged into the bottles, but, fur- 40 thermore, I provide an arrangement whereby the same pipes and passages which effect a discharge of the liquid from the main to the subreservoirs are also employed as the means for effecting a discharge of the liquid from the subreservoirs to the bottles, thus giving 45 the said pipes a double function, so to speak, and thereby simplifying the machine and rendering it extremely satisfactory and service- able in use.

What I claim as my invention is—

50 1. A machine for filling bottles, comprising a main reservoir, a subreservoir, an endwise- adjustable pipe adapted in its normal position to establish communication between the main reservoir and the subreservoir, but 55 adapted in its endwise-adjusted position to cut off communication between the main reservoir and subreservoir and establish communication between the subreservoir and the bottle or other receptacle to be filled, a suitable sup- 60 port for the bottle or receptacle, and manually- operated devices for adjusting said pipe.

2. A bottle-filling machine comprising a main reservoir, a subreservoir provided with

an air-vent consisting of a vertically-adjustable or vertically-disposed pipe, a vertically- 65 disposed and endwise-adjustable pipe adapted in its normal position to establish communica- 70 tion between the main reservoir and the subreservoir, but adapted in its lowered or adjusted position to cut off said communica- 75 tion and establish communication between the subreservoir and the bottle or receptacle to be filled, a support for the bottle or receptacle, and manually-operated devices for adjusting said last-mentioned pipe. 75

3. A machine for filling bottles, comprising main and sub reservoirs, and an endwise-adjustable pipe extending through both reservoirs, said pipe being provided with lateral 80 openings adapted to normally establish communication between the two reservoirs, but adapted when the pipe is adjusted endwise to cut off said communication and establish communication between the subreservoir and the bottle or receptacle to be filled, and suitable 85 devices for adjusting said pipe. 85

4. A bottle-filling machine comprising a reservoir, an endwise-adjustable pipe adapted when adjusted to a lower position to establish communication between the reservoir and the 90 bottle or receptacle to be filled, a funnel- shaped guard slidably mounted on the lower portion of said pipe, a support for the bottle or other receptacle, and suitable devices for adjusting said pipe. 90

5. A bottle-filling machine comprising a main reservoir, a plurality of subreservoirs, each subreservoir consisting of a glass cylinder clamped to the bottom of the main reservoir by means of clamping-bolts and bottom 100 plates, vertically-adjustable vent-pipes ex- 105 tends downwardly into said subreservoirs, vertically-adjustable pipes extending through both the main and sub reservoirs, said last- mentioned pipes being provided with lateral 110 openings adapted normally to establish communication between the main and sub reservoirs, but adapted when the pipes are ad- 115 justed to cut off said communication and es- tablish communication between the subreser- 115 120 voirs and the bottles or receptacles to be filled, a support for the bottles or other receptacles, and suitable devices for adjusting said last-mentioned pipes. 120

6. A bottle-filling machine comprising main 115 and sub reservoirs, vertically-disposed and endwise-adjustable vent-pipes for said sub- reservoirs, vertically-disposed and endwise- adjustable refilling and discharge pipes for said subreservoirs, a vertically-adjustable sup- 120 port for the bottles or other receptacles to be filled, and suitable devices for adjusting said last-mentioned pipes. 120

7. A bottle-filling machine comprising a suitable main frame, a main reservoir mounted upon the upper portion of said main frame, 125

subreservoirs depending from said main reservoir, vertically-adjustable vent-pipes for said reservoirs, vertically-adjustable refilling and discharge pipes for said subreservoirs, 5 suitable devices for simultaneously adjusting said last-mentioned pipes, springs for holding said refilling and discharge pipes in their normal positions, a vertically-adjustable support for the bottles or other receptacles to be filled,

and funnel-shaped guards slidably mounted 10 on the lower end portions of said last-mentioned pipes.

Signed by me at Chicago, Cook county, Illinois, this 17th day of October, 1903.

WILLIAM F. FANNING.
